UNITED STATES PATENT OFFICE.

CHARLES J. SHUTTLEWORTH, OF SPRINGVILLE, NEW YORK.

GOVERNOR FOR WATER-WHEELS.

SPECIFICATION forming part of Letters Patent No. 295,060, dated March 11, 1884.

Application filed May 22, 1883. (No model.)

To all whom it may concern:

Be it known that I, CHARLES J. SHUTTLEWORTH, of Springville, in the county of Erie and State of New York, have invented new and useful Improvements in Governors for Water-Wheels, &c., of which the following is a specification.

This invention relates to an improvement in governors for water-wheels and other motors to in which the supply of water or other actuating agent is regulated by a ball-governor, and has for its object to so construct the governor that the normal speed of the water-wheel or other motor or engine can be increased or reduced by a simple adjustment of the governor, and without requiring a change in the size of any of the parts, as heretofore.

A further object of my invention is to prevent the great variations in the speed and water-supply, which occur when these governors are used, and to render the water-supply more regular and the speed more uniform than heretofore.

My invention consists, to these ends, of the improvements in the governor, which are hereinafter fully set forth, and pointed out in the claims.

In the accompanying drawings, consisting of two sheets, Figure 1 is an elevation of my improved water-wheel governor. Fig. 2 is a top plan view thereof. Fig. 3 is an elevation at right angles to Fig. 1. Fig. 4 is a sectional elevation of the spindle and connecting parts on an enlarged scale. Fig. 5 is a perspective view of the spring.

Like letters of reference refer to like parts in the several figures.

A represents the stationary frame of the governor.

b represents a horizontal shaft supported in bearings b', which are secured to the top pieces of the frame A.

B is a pulley, which is secured to the shaft b and rotated by an endless belt from a suitable part of the machinery which is driven by the water-wheel. The shaft b may be driven by gear-wheels, if preferred, or by any other suitable transmitting mechanism, so that its rotation bears a fixed relation to the speed of the driven machinery.

c represents the spindle or vertical shaft,

provided at its upper end with a bevel-wheel, c', which meshes with a bevel-wheel, c'', on the shaft b, so that the spindle is rotated from the shaft b. The upper end of the spindle 55 is supported in a bearing, d, in such manner that the spindle can move vertically in the same. The bearing d is attached to a bridge-tree or cross-piece, D, forming part of the stationary frame. The lower end of the spindle 60 is supported in a step, e, which is formed on an adjustable bridge-tree, E. The latter rests with one end upon a plate, f, secured to one of the bottom sills of the frame A, or it may be pivoted to said plate, if preferred, in such 65 manner that the opposite end of the bridge-tree can be raised or lowered at desire. The free end of the bridge-tree E is provided with a vertical set-screw, g, which works in a screw-threaded opening in the bridge-tree and rests 70 upon a wear-plate, g', secured to one of the bottom sills of the frame A. The upper end of the set-screw g is provided with a hand-wheel, g'', whereby it is turned. Upon turning the screw g the bridge-tree E and the spindle c, resting thereon, are raised and lowered. 75 g'' is a jam-nut applied to the screw g above the bridge-tree E for locking the latter in position after it has been adjusted.

h is the horizontal shaft, whereby the position of the gate is controlled. The shaft is supported in bearings h', secured to the frame A, and provided with a pulley, H, to which an endless belt is applied, whereby the shaft h is connected with the mechanism for opening and closing the gate in such manner that by turning the shaft h in one direction the gate will be opened, while by turning said shaft in an opposite direction the gate will be closed.

I is a gear-wheel secured to the shaft h, and i is a pinion which meshes with the wheel I, and is loosely mounted on a horizontal shaft, j. The latter turns in bearings j', secured to cross-pieces of the frame A, and its axis intersects the axis of the spindle c at right angles. The pinion i is detachably connected with the shaft j by a clutch-coupling, J, so that the pinion can be caused to turn with the shaft or loosely on the shaft at will upon shifting 95 the coupling J by means of its shifting-lever k.

L represents a hand-wheel secured to the

end of the shaft h , for turning the latter and adjusting the gate by hand when the coupling J has been disengaged from the pinion i .

M represents a bevel friction-wheel mounted 5 on the shaft j , and provided, preferably, with a facing of paper or other material which possesses the requisite degree of adhesiveness.

N N' are two similar friction-wheels arranged upon the spindle c , above and below 10 the friction-wheel M , and secured together by a sleeve, n , which surrounds the spindle. The latter is provided with a key or feather, n' , which projects into a groove in the bore of the sleeve n and causes the latter to move with 15 the spindle, while permitting the sleeve to move vertically on the same. The wheel N is adapted to engage against the upper side of the wheel M , and the wheel N' is adapted to engage against the lower side of the wheel M , 20 and both wheels N N' are arranged so far apart that one will clear the wheel M when the other runs in contact therewith, and that both wheels can be so adjusted as to clear the wheel M .

25 Instead of constructing the wheels M N N' in the form of bevel-wheels, as shown, the wheels may be made in the form of plain cylindrical disks; but I prefer the construction shown, as it is more effective. The wheels may be constructed with teeth, if preferred.

o represents the governor-balls, and o' the arms, whereby they are connected with a cross-head, o^2 , secured to the spindle c , below the wheel N' .

35 p are links whereby the arms o' are connected with the wheel N' , the links being pivoted to lugs p' on the arms and lugs p^2 on the under side of the wheel N' , so that the wheels N N' are raised when the balls o separate, and lowered as the balls approach each other.

40 r is a curved spring, which connects the wheel N' with the spindle c . The spring r is secured with its upper end to the wheel N' , and with its lower end to a collar, s , which is adjustably secured to the spindle by a set-screw, or otherwise. By raising or lowering the collar s on the spindle the tension of the spring r , the position of the wheels N N' with reference to the wheel M and the normal position 45 of the balls can be regulated. The motion which is imparted to the shaft b by the driven machinery is transmitted to the spindle c by the bevel-wheels c' c^2 . The spindle is so adjusted by the bridge-tree E that the wheels N 50 N' will run clear of the wheel M when the spindle rotates with the normal speed. When the motion of the spindle falls below the normal speed, the balls o approach each other, the wheel N comes in contact with the upper 55 side of the wheel M , and the motion of the latter is transmitted by the shaft j and pinion i to the wheel I and shaft h in a direction in which the gate controlling the supply of water to the water-wheel will be opened and the 60 water-supply be increased. As the speed of the spindle increases by the increased supply

of water, the balls diverge and raise the wheel N from the wheel M , thereby stopping the mechanism by which the gate is operated. If the acceleration of speed should continue, the 70 lower wheel, N' , will come in contact with the lower side of the wheel M , and turn the latter and the gate mechanism in an opposite direction, whereby the water-supply is correspondingly reduced. The vertical movements of 75 the wheels N N' on the spindle c and the movements of the governor-balls cause a deflection of the spring r out of its normal position. By adjusting the tension of the spring the movement of these wheels and balls can 80 be nicely regulated, so that the proper supply of water and the normal speed are maintained with greater regularity or much small variations than in ordinary governors, which cause alternately an excessive and deficient water-supply and corresponding irregularities of 85 speed. If it is desired to increase the speed, the spindle c is lowered by the bridge-tree E , so that a greater speed will be attained before the lower wheel, N' , comes in contact with 90 the wheel M and reduces the water-supply. If a slower movement is desired, the spindle is correspondingly increased by the bridge-tree. These adjustments of the spindle do not affect the adjustment of the spring r , which 95 moves with the spindle. The spring is so adjusted that it will be deflected out of its normal position by the governor-balls when the latter move out of their normal position. The spring offers therefore a resistance which 100 retards the governor-balls in moving out of their normal position, and the range of movement of the governor-balls is thereby considerably reduced, and the supply of water or other actuating agent to the machinery more 105 perfectly controlled and rendered more uniform.

My improved governor may, with certain obvious modifications in construction, be employed in connection with steam-engines.

I claim as my invention—

1. The combination, with a ball-governor, of a spring secured with one end to the spindle of the governor, and with its opposite end to a collar or sleeve which is moved by the 115 governor-balls, the spring being adapted to resist any movement of the governor-balls out of their normal position in either direction, substantially as set forth.

2. The combination, with mechanism whereby the supply of water or other actuating agent is controlled, of a ball-governor, a spindle to which the governor-balls are attached, and an adjustable step supporting said spindle, whereby said spindle can be raised or lowered to 120 regulate the normal speed of the machine, substantially as set forth.

3. The combination, with a vertical spindle, and mechanism whereby the same is rotated, of the connected wheels N N' , mounted 125 on the spindle, an intermediate wheel, M , connected with the gate mechanism, a ball-gov-

ernor connected with the wheels N N' , and mechanism whereby the spindle can be raised and lowered, substantially as set forth.

4. The combination, with the spindle c , of 5 the connected wheels N N' , a ball-governor, o , connected with said wheels, and a spring connecting said wheels with the spindle, substantially as set forth.

5. The combination, with the spindle c and 10 connected wheels N N' , of a spring connecting said wheels to the spindle, and made adjustable on the spindle, substantially as set forth.

6. The combination, with the spindle c , connected wheels N N' , and a ball-governor connected with said wheels, of the wheel M , shaft 15 j , coupling J , pinion i , gear I , gate-shaft h , and wheel H , substantially as set forth.

7. The combination, with the wheel M ,

whereby the gate mechanism is actuated, of the spindle c , connected wheels N N' , mounted 20 on said spindle, and a ball-governor mounted on the spindle, and an adjustable bridge-tree, E , on which the spindle is supported, substantially as set forth.

8. The combination, with the wheel M , 25 whereby the gate mechanism is actuated, of the spindle c , connected wheels N N' , a ball-governor connected with the spindle and the wheels N N' , a spring, r , whereby the wheels N N' are connected with the spindle, and an 30 adjustable bridge-tree, E , upon which the spindle is supported, substantially as set forth.

C. J. SHUTTLEWORTH.
